UNITED STATES PATENT OFFICE.

JOSEPH T. BAILEY, OF PHILADELPHIA, PENNSYLVANIA.

DESIGN FOR A BADGE.

SPECIFICATION forming part of Design No. 36,042, dated September 9, 1902.

Application filed August 16, 1902. Serial No. 119,971. Term of patent 14 years.

To all whom it may concern:

Be it known that I, JOSEPH T. BAILEY, a citizen of the United States, residing in the city and county of Philadelphia, State of Pennsylvania, have invented and produced a new, original, and ornamental Design for a Badge, of which the following is a specification, reference being had to the accompanying drawings, forming part thereof.

10. My design consists of the representation of a dragon surmounted by the representation of a dragon's egg and flambeaux.

Figure 1 represents a view of the obverse face of a badge embodying my design. Fig. 2 represents a view of the reverse face thereof.

15. In the drawings, A represents a circular plate, on the obverse face of which is the rep-

resentation of a dragon B, having a grotesque head C, a sinuous body D, and claws E. Surmounting said plate is the representation of 20 a dragon's egg F, which is seated in the representation of the flame G, and the representation of flambeaux H on the ends of the representation of said egg.

Having thus described my invention, what 25 I claim as new, and desire to secure by Letters Patent, is—

The ornamental design for a badge substantially as shown and described.

JOS. T. BAILEY.
